D. Clyde Jones
ATTORNEY

UNITED STATES PATENT OFFICE

ARTHUR E. HETZNER, OF EAST ORANGE, NEW JERSEY, ASSIGNOR TO GRAYBAR ELECTRIC COMPANY, INC., OF NEW YORK, N. Y., A CORPORATION OF NEW YORK

MULTIPLE PUSH-BUTTON UNIT

Application filed April 17, 1929. Serial No. 355,869.

This invention relates to equipment for use in telephone systems and more particularly to a push button unit for use in an interconnecting system.

The present invention has for its purpose the provision of a multiple push button unit which may be mounted in the dial opening of a standard telephone. A further purpose of the invention is the provision of such a push button unit which is inexpensive to manufacture and which can be used with varying numbers of buttons, without changing the structure, merely by inserting additional buttons in spaces already provided.

The above features and others will appear from the detailed description and claims when taken with the drawings in which Fig. 1 is a portion of a desk telephone having the unit of the present invention mounted therein; Fig. 2 is a section through the center of the unit; and Fig. 3 is a similar enlarged section of a fragment of the unit showing one of the buttons in operated position; while Fig. 4 shows the parts of the unit in position ready for assembling.

Although the invention may be used with any type of telephone having an opening in its casing, it is particularly adapted for use in a desk telephone such as shown in Fig. 1 having a base 5 with an opening therein and with an off-set column 6 which may carry a transmitter or a cradle for supporting a combined microphone and receiver. The present multiple button unit is shown in Fig. 1 mounted in the opening in the base 5 which is normally provided to receive an impulse transmitter or dial used in an automatic telephone system.

This unit, as best shown in Figs. 2, 3 and 4, comprises a circular mounting plate 8 having a plurality of openings 9 to receive push buttons 10. On the under side of the mounting plate 9 but spaced therefrom by a metal washer 13 there is supported a multiple spring contactor 11 having integral

fingers 12. Beneath the spring contactor but spaced therefrom by a metal washer 14, there is placed a disc 15 of insulating material having screw contacts 16 to which ringing conductors may be connected and with which the spring fingers 12 may engage. These parts are held in the position shown in Fig. 2 by means of three screws 17 passing therethrough. On the top of the mounting plate 8 there is placed a circular designation sheet 18 having an opening 19 for each of the push buttons 10 that are used while a protective, transparent sheet 20, with holes 21 to receive these push buttons, serves to protect the designation sheet. A flange ring 22 fastened by screws such as 23 to the mounting plate 8 holds the two sheets in position.

What I claim is:

1. In combination with a telephone case having an opening therein adapted to receive an automatic telephone impulse transmitter, a multiple push button unit mounted in said opening comprising a support carrying a plurality of contacts, a contactor co-operating with said contacts, and a plurality of buttons mounted for selectively actuating said contactor to engage a desired contact.

2. In combination with a telephone case having an opening therein adapted to receive an automatic telephone impulse transmitter, a multiple push button unit mounted in and closing said opening, comprising a support carrying a plurality of contacts, a contactor having an integral spring in co-operative relation with each contact, and a plurality of buttons for selectively actuating said contactor springs to engage desired contacts.

3. In combination with a telephone case having a circular opening therein adapted to receive an automatic telephone impulse transmitter, a circular multiple push button unit mounted in and closing said opening, com-

prising a support carrying a plurality of individual contacts, a contactor having an integral conducting spring in cooperative relation to each contact, and a button mounted above each of certain of said springs to force its related spring into engagement with a desired contact.

4. In combination with a telephone base having an opening therein adapted to receive an automatic telephone impulse transmitter, a multiple push button unit mounted in said opening comprising a mounting plate having a series of openings therein, push buttons in said openings, a contactor mounted in spaced relation to said mounting plate but with said buttons in operative relation with respect thereto, and a piece of insulation spaced from said contactor, said piece carrying contacts in position to be engaged by said contactor.

5. In combination with a desk telephone having a base and an off-set column, a circular opening in said base adapted to receive an automatic telephone impulse transmitter, a multiple push button unit mounted in and closing said opening, comprising a mounting plate having a series of openings therein positioned to describe a circle, push buttons in said openings, a contactor in spaced relation to said mounting plate, said contactor having integral fingers radiating toward said openings in said plate and adapted to be engaged by said push buttons, and a piece of insulation spaced from said contactor, said piece carrying contacts positioned to be engaged by said fingers.

6. In combination with a desk telephone having a base and an off-set column, said base being provided with an eccentric circular opening, a multiple push button unit adapted to be mounted in and to close said opening, comprising a mounting plate having a series of openings therein positioned to describe a circle, a contactor fastened to said mounting plate in spaced relation thereto, said contactor being formed of integral contacting fingers provided with down-turned ends adapted to be depressed by said push buttons, and a circular piece of insulation spaced from said contactor and supported by said mounting plate, said piece carrying contacts in position to be engaged by the down-turned ends of said contacting fingers.

7. In combination with a desk telephone having a circular base, an off-set column mounted thereon, said base having an eccentric opening, a multiple push button unit mounted in and adapted to close said opening, comprising a circular mounting plate having a series of openings therein positioned to describe a circle, push buttons in said openings, a contactor fastened to said mounting plate in spaced relation thereto, comprising integral fingers provided with down-turned ends radiating toward said openings

in a position to be depressed by said push buttons, and a circular piece of insulation supported from said mounting plate in spaced relation to said contact fingers, said piece of insulation being provided with contacts 70 mounted in circular position about the periphery thereof, each of said contacts comprising a screw passing through the piece of insulation and fastened thereon by a nut.

In witness whereof, I hereunto subscribe 75 my name this 10 day of April, A. D. 1929.

ARTHUR E. HETZNER.
